SAFETY HAT

Herbert A. Raschke, Greenbrae, Calif., assignor to
E. D. Bullard Company, Sausalito, Calif.

Filed Jan. 29, 1965, Ser. No. 83,622

Term of patent 14 years

(Cl. D3—13)

FIG. 1 is a top perspective view of a safety hat showing my new design;

FIG. 2 is a side elevational view, the side opposite being a mirror image thereof;

FIG. 3 is a front elevation view;

FIG. 4 is a rear elevation view;

FIG. 5 is a top view; and

FIG. 6 is a bottom view.

The essential features of my design reside in the full line disclosure on the drawing.

I claim:

The ornamental design for a safety hat, as shown and described.
